DESIGN FOR A DOUBLE CLIP PIN

Ernest Steiner, New York, N. Y.

Application March 19, 1934, Serial No. 51,103

Term of patent 3½ years

To all whom it may concern:

Be it known that I, ERNEST STEINER, a citizen of the United States of America, residing at 339 Fifth Avenue, Manhattan, in the county of New York and State of New York, have invented a new, original, and ornamental Design for a Double Clip Pin, of which the following is a specification, reference being had to the accompanying drawing, forming part thereof.

I claim:

The ornamental design for a double clip pin as shown.

ERNEST STEINER.
